HYDRAULIC WELL DRILLING DEVICE

Eugen Merten, Houston, Tex., assignor to Shell Development Company, San Francisco, Calif., a corporation of Delaware

Application June 19, 1944, Serial No. 540,989

9 Claims. (Cl. 255—4.4)

1

The present invention pertains to the drilling of wells, exploratory boreholes and the like, and relates more particularly to an improved hydraulic drilling device.

Both rotary tools and cable tools of the percussion type are commonly used for drilling. Rotary drilling is especially advantageous because it gives a high speed of penetration in relatively soft formations, and because it is suitable for use at great depths. Rotary drilling, however, is relatively inefficient in very hard formations, since rotary bits, even of the hard-faced or diamond-set types, are in such cases subject to a high rate of wear and require constant replacement. Cable tools, while most effective in hard formations, are limited in their use to relatively shallow depths.

It is therefore an object of this invention to provide a drilling device especially adapted for drilling, at any desirable depth, through extremely hard formations, the impact action of the considerable mass of the present drilling device being effective in cracking thin formations or layers of hard rock. Since this impact action is not dependent on the degree of sharpness of the drill bit, the necessity of replacing worn out bits is reduced to a minimum, and a rapid rate of penetration into either thin or thick hard formations is achieved.

It is also an object of this invention to provide a hydraulic drilling system wherein the reciprocating action of a percussion type bit is controlled by a valve responsive to differential pressures generated by the flow of a hydraulic or pressure fluid through the bit.

It is also an object of this invention to provide a hydraulic drilling device of the percussion type capable of operating with a variable downward stroke, which is independent of the physical dimensions of the reciprocating members involved, whereby the necessity of rigorously maintaining the drilling device at a critical distance from the bottom of the hole is eliminated without impairing the efficiency of the operations.

It is also an object of this invention to provide a drilling system which combines the grinding action of the rotary tool with the reciprocating or impacting action of the cable tool, and thus possesses the advantages of both drilling methods.

It is also an object of this invention to provide a drilling system wherein a rotary and a reciprocating motion is imparted to the bit by hydraulic means, that is, by supplying to the bit an actuating stream of a pressure liquid through a drill string such as used in rotary systems.

It is also an object of this invention to provide

2

a drilling system adapted to drill boreholes having a diameter larger than that of the drill bit used in drilling.

It is also an object of this invention to provide a drilling system wherein a dangerously worn condition of the drill bit is indicated to the operator by a rise in the pressure of the hydraulic fluid, and the drilling is automatically stopped by means positioned within the bit.

10 These and other objects of this invention will be understood from the following description, taken with reference to the attached drawings, wherein

Fig. 1 is a diagrammatic view in vertical cross-section of a preferred embodiment of the present drilling device;

Fig. 1A is a fragmentary view of a modification of the device of Fig. 1;

Fig. 2 is another view of a modification of the device of Fig. 1;

Fig. 3 is a diagrammatic view in vertical cross-section of another embodiment of the present drilling device;

Fig. 4 is a similar view of a modification of the device of Fig. 3;

Fig. 5 is a horizontal cross-section view taken along line 5—5 of Fig. 3;

Figs. 6 and 7 are, respectively, an elevation and a horizontal cross-section view of a drill bit suitable for use with the system of the present invention;

Figs. 6A and 7A are similar views of another bit suitable for use with the system of the present invention;

Figs. 8 and 9 are similar views of another bit suitable for use with the system of the present invention;

Fig. 10 is a view, partly in cross-section, of the present drilling device provided with a clutch arrangement for rotary application;

Figs. 11 and 12 are diagrammatic views of a bit arrangement adapted to prevent damage to the mechanism of the present drilling device through the wear of the drill bit;

Fig. 13 is a diagrammatic view in cross-section of a valve arrangement adapted to maintain the hydraulic fluid of the present system within predetermined pressure and circulation volume ranges;

Fig. 14 is a view, partly in cross-section, of a modification of the upper part of the mechanism shown in Figs. 1 and 2.

Referring to the drawings, Fig. 1 shows in diagrammatic form a preferred embodiment of the present hydraulic drilling device, all conventional

details such as couplings, screw-threads, etc. being omitted for clearness.

The hydraulic drilling device is supported on a drill string or stem 1 from the surface, where suitable equipment, such as pumps, valves, etc., is provided to flow a stream of fluid such as water, oil, drilling fluid, etc. down said string. The lower end of the drill stem may be somewhat enlarged to form a chamber 15, and is closed at the bottom by a plate 19 having therethrough a central passage 16. A spider plate 13, having passages 13A therethrough, supports a plate or cap member 11 within chamber 15 above the passage 16. Lateral ports 9 provide for fluid communication between the inside and the outside of the string 1.

The drill stem together with elements 15 and 19 forms a stationary piston member with regard to a movable cylinder member 5, having a central bore 7 adapted to fit slidingly about said piston, said cylinder being suitably closed at the top and at the bottom, as shown at 2 and 20. Packing elements may be provided between the piston and cylinder members as shown at 3 and 17. The lower part of the cylinder 5 may be integral with, or may have attached thereto, a cutting element or a drill bit having any desired number of cutting blades 27, such for example as a fishtail bit.

Carried within the piston 15 between the transverse plates 13 and 19 is a movable valve member 8, having a cup-shaped hollow upper portion 4A and, if desired, an elongated stem member 18 depending therefrom. A very small-diameter channel 12 is in fluid communication between the space 4 within the hollow valve portion 4A and the space outside of said valve. The size and shape of the member 8 and of the channel 12 are selected so that the outer orifice or orifices of said channel are at the level of a constricted part of the flow passage through the piston when the cup member 4A abuts the cap member 11, for example, as shown in Fig. 1, for purposes to be described hereinbelow. The piston passage 16 is provided with seat 14 for the valve member 8, which is adapted to close said passage when moved into its lowermost position as shown in Fig. 2.

Exhaust means, such as a passage 25, are provided for flushing into the borehole the fluid from the space within the cylinder.

A pin or finger member, such as a spring 21 is provided within the lower portion of the cylinder 5 in register with the stem 18 of the valve, being supported for example by means of a web structure 23.

The operation of the present drilling device is as follows: a hydraulic fluid is forced under pressure downwards through the drill string 1, the valve 8 being at that time in its lowermost position against the seat 14. The central passage 16 being thus closed, as shown in Fig. 2, the fluid passes through the ports 9, and the pressure developed within the bore or space 7 above the piston forces the cylinder 5 upwards with regard to the stationary piston 15—19 thus raising the bit 27.

As the moving cylinder comes to the upper limit of its stroke, the pin or spring means 21 strikes the valve 8 and raises it until it comes in contact with the cap 11. The passage 16 being thus open, the hydraulic fluid flows therethrough from the drill string 1, and also from the space 7 of the cylinder, and out into the borehole through the passage 25. The cylinder 5 moves down by gravity, impacting the blades 27 against the bottom of the borehole. As the downward motion of the cylinder begins, the yieldable means 21,

previously compressed against the valve 8, expands to its full non-stressed length, thereby still remaining in contact with said valve during a short initial period of the downward stroke. This 5 maintains the valve 8 pressed against the cap 11 during said initial period, and permits the flow of the fluid through the piston to create, by the Venturi effect, a pressure differential between the relatively restricted passage 16 and the space 10 above and below. The reduced pressure within the restricted passage is transmitted, through the channel 12, to the space 4 within the cup-shaped valve, whereby said cup is firmly held by said pressure-differential or suction-cup effect, against 15 the cap member 11 during the downward stroke.

As the bit strikes the bottom of the borehole, and the downward motion of the cylinder 5 is stopped, the rate of the fluid flow through the passage 16 is decreased, no more fluid flowing from the space 7. The differential pressure holding the valve 8 up is thus decreased; and the valve drops down on the seat 14, closing the passage 16, whereafter the upward stroke of the cylinder is repeated.

Instead of the construction shown in Fig. 1, the cup-shaped valve member 8 may be formed without the depending projection 18, as shown in Fig. 1A. In this case, the low pressure prevailing under fluid flow conditions in the relatively constricted passage 13B is applied by means of a small communication passage or channel 12A to the inside of the cup 8A, which is thus maintained pressed, by the relatively higher pressure in space 15A, against the cap 11A during the downward motion of the movable member. The operation of the device of Fig. 1A is in all other regards identical with the operation of that of Fig. 1.

It will therefore be seen that the valve structure of the present hydraulic drilling device has the advantage of not requiring any spring means for holding said valve in position, the holding effect being provided by pressure differential means, and all difficulties usually encountered in adjusting valve springs for properly timed operation under conditions of varying pressures being thereby eliminated. The great advantage of the present system resides however in its ability to operate with a variable length stroke. It will be seen that with the arrangement shown, valve 8 will close and thereby reverse the direction of the stroke whenever the bit hits the bottom of the borehole and thereby arrests the downward motion of the cylinder, whether or not the cylinder has at this moment reached the lower limit of its stroke, as determined by its position with regard to the stationary piston. The present variable stroke system thus eliminates the necessity of continuously and accurately correlating the level of the piston 15, that is, the length of the drill string, with the level of the bottom of the borehole or with the rate of penetration of the bit.

Fig. 2 shows a hydraulic bit similar to that of Fig. 1 and operating on the same principle, but provided with an additional spring 31, which is compressed between the stationary piston and the bottom of the movable cylinder during the upward stroke of the latter. The spring 31 serves to accelerate the bit additionally to the effect of gravity during the downward or impact stroke.

The bit of Fig. 2 is also provided with a valve 35, which serves to close the exhaust passage 25 through the bit when depressed downwards against the action of a spring 37, engaged between said valve and a spider 38 and tending to hold the valve up.

The operation of this valve is as follows: when the cylinder 5 is about to reach the end of its upward stroke, the spring 33 which corresponds to the spring 21 of Fig. 1, lifts the upper valve 8 from its seat, opening the passage 16. The valve 8 is pressed against the cap 11 and acts to compress first the spring 33 and then the spring 37, thus closing the lower valve 35. As the cylinder reverses its motion, the bit is impacted against the formation by the triple effect of gravity, of the spring 31, and of the hydraulic pressure of the fluid passing through passage 16 and acting against the lower inner face 40 of the cylinder, which is greater than the upper inner face thereof by an area equal to the cross-sectional area of the tubular string 1, said pressure acting at the same time to hold the valve 35 closed against the action of spring 37.

As the bit hits the bottom, and the downward motion of the cylinder is arrested, the flow of fluid through the passage 16 to the lower portion 32 of the cylinder ceases, the collapse of the differential pressure generated by said flow permits the valve 8 to drop to its seat, closing the passage 16, and the fluid pressure applied through the ports 9 to the upper portion 7 of the cylinder starts a new cycle by raising the cylinder. The pressure in the portion 32 of the cylinder below the piston is at that time relieved by fluid leakage through a small-bore channel or passage 39 between the inside and the outside of the cylinder, which permits the spring 37 to overcome said pressure and to raise the valve 35, thus opening the passage 25 and allowing the fluid from space 32 to flow into the borehole during the upward stroke of the cylinder.

Although, as seen from the above, Fig. 2 differs from Fig. 1 by the inclusion of two additional elements, namely the spring 31 and the valve 35, it is obvious that the device of Fig. 1 can also be modified by adding thereto only one of said elements.

Figs. 3 and 4 show bits similar in operation to those of Figs. 1 and 2, but in which the cylinder is stationary, being attached to the drill string, while the bit is attached to a piston movable within said cylinder.

The lower portion of a drill string 51 forms or has affixed thereto an outside housing 53, which may be of a somewhat enlarged diameter as shown in the drawing.

Arranged concentrically with the outside housing 53 is an inside housing or cylinder 80, attached thereto by a lower flange 85, or by a spider or web structure 55, or both, said spider serving as a top closure for the inner cylinder and the flange 85 serving as bottom closure for both housings or cylinders. The inside cylinder 80 has in its lower portion passages or openings 83 in communication with the space within the outside housing 53. Arranged for reciprocating action within the cylinder 80 is a piston 65, having attached thereto a tubular member or piston rod 81, which passes slidably through the flange 85 and carries attached to its lower end a bit 89. The piston rod has a bore 82, opening at the upper end to the space above the piston, and in register at the lower end with a passage 91 through the bit for exhausting the drilling or hydraulic fluid from the cylinder into the borehole. Packing means 67 and 87 are provided to prevent loss of fluid during the reciprocating action of the piston, as shown in the drawing.

The piston 65, as seen from Figs. 3 and 5, has a plurality of laterally arranged axial passages 64

surrounding the central bore 82 of the piston rod and opening into an annular opening 69, which forms a valve seat for a valve structure adapted to be closed when a valve member 73 is seated thereon.

The hollow or cup-shaped valve member 73 has a central opening slidingly fitting around the piston rod 81, its downward motion along the stem being limited by a stop member 79, affixed to the rod 81, and serving as a closure for the open end of the cup-shaped valve member when the latter is in its lowermost position. A spring 75, positioned around the rod 81 within the hollow valve 73, is likewise supported by the stop or plate 79, and tends to force the valve 73 against its seat 69. Small-diameter channels 71 are provided through the walls of the piston rod 81 for fluid communication between the bore of said rod and the inside of the hollow valve.

Link members 71 are affixed to the valve 73 and pass through the openings 69 and 64, being connected above the piston to a spider or web member 63, having orifices 61, said spider being thus adapted to move together with the valve 73.

A powerful spring 59 is held in compression between the piston 65 and the upper closure 55 of the inner cylinder. Pin or finger means such as a stem, tappet or spring 57, affixed to the top closure of the cylinder, extend downwards into the cylinder, concentrically and within the spring 59.

The operation of the variable stroke system of Fig. 3 is as follows:

The spring 75 expands and forces the hollow valve 73 against its seat 69, thus closing the piston 65 against fluid flow. The pressure fluid supplied from the surface through the string 51 enters the lower portion of the inner cylinder 80 through the ports 83 and forces the piston 65 upwards, compressing the spring 59 and helping the spring 75 to maintain the valve 73 closed against the seat 69. As the piston 65 approaches the upper limit of its stroke, the pin or spring 57 strikes the spider 63 and forces the valve 73 downwards. The hydraulic fluid flows now through passages 64, piston rod bore 82 and passage 81 into the borehole, while the piston 65 and the bit 89 travel downward under the effect of gravity and of the spring 59.

The spring 57 expands and acts to maintain the valve 69-73 open during the initial moments of this downward stroke. As the spider 63 moves downward and out of contact with spring 57, however, the tendency of the valve 73 to close under the action of spring 75 is counteracted by the fact that, due to the Venturi effect already mentioned with regard to Fig. 1, the pressure within the relatively constricted bore 82, which is applied to the inside of the hollow valve member 75 through the passages 71, is lower than the pressure in the cylinder space 66 outside said hollow valve member, which is therefore maintained in its lowermost position against the effect of spring 75 by the pressure differential thus created.

As the bit 89 hits the bottom of the borehole, and the downward motion of the piston 65 is arrested, the flow rate through the space 66 and tubing 81 decreases. The decrease of the pressure differential permits the spring 75 to close the valve 69-73, and the cycle is repeated.

It is obvious that the spring 59 may be omitted, in which case the downward stroke of the bit is effected only under the action of gravity.

The embodiment of Fig. 4 differs from that of Fig. 3 in that the central axial flow passage

through the piston 115 is provided with a closure or cover member 114, which is maintained in open position by a spring 119 positioned within the piston rod bore 82 and supported by means of a spider or rim member 120. The cover 114 has a small-diameter channel or orifice 113 therethrough.

The hollow valve 123 is similar to valve 73 of Fig. 3, but has a small-diameter channel 127 in communication between the space within the hollow valve and the passage 124 through the piston. Passage 127 corresponds in its functions to passage 77 of Fig. 3.

The space above the piston 115 comprises, besides the springs 57 and 59, identical to those of Fig. 3, also a pin or spring member 108 adapted to register with and to close the cover 114 at the end of the piston's upward stroke.

The operation of the system of Fig. 4 is similar to that of Fig. 3, excepting that, upon the end of the upward stroke, the spring 108 closes the cover 114 and the piston and bit structure is then forced down by the combined effect of gravity, action of the spring 59, and pressure of the hydraulic fluid applied to the top of the piston. The hollow valve 123 is maintained in its open position during the downward stroke by the differential pressure existing between the space 129 outside the hollow valve, and the relatively narrow passage 124, the lower pressure within said passage 124 being applied to the inside of the hollow valve by means of the channel 127.

When the bit hits the bottom of the borehole, and the downward stroke is thus ended, the spring 75 closes the bell valve due to the collapse of the pressure differential. At the same time, a leakage of the fluid through the small-diameter channel 113 relieves the pressure in the space above the piston and permits the spring 119 to lift the closure 114. The hydraulic fluid admitted through the string 51 to the space below the piston then moves the piston upwards, driving the fluid from the space above the piston into the borehole through the piston rod bore 82.

Figs. 6 and 7 show a tubular bit member 101, which may be similar to the members 5-27 of Figs. 1 and 2, or to members 81-89 of Figs. 3 and 4, and which is provided with blade elements 104, similar to elements 25 and 91 of said figures, respectively. In order to impart to this bit not only the reciprocating or impact action described above, but also a rotary or grinding action, the hydraulic liquid passages through the bit may be given, if desired, an arcuate or spiral form such as shown at 103 in Fig. 7, whereby the bit is rotated by the repelling force of the pressure liquid issuing therefrom. The twist of the passage 103 should be in such a direction as to produce rotation giving a tightening action on the threads connecting the bit to the drill string. It may be noted that this method, inoperative in conventional rotary drilling, where the bit drags at all times on the bottom of the borehole, is extremely effective with the present system, the rotating motion being imparted to the bit at such times as it is traveling upwards or downwards, and is therefore not in frictional engagement with the bottom of the borehole.

When it is desired to impart to the bit a rotary motion from the surface, for example by means of a conventional rotary table, driving the drill string, the cylinder and piston members shown in Figs. 1-4 may be provided with splines, keys, keyways and the like in order to prevent their rotating with regard to each other. Since, however,

it is difficult to keep such splines and keyways well fitted under conditions involving a rapid reciprocating action in a medium such as water or especially drilling fluid, it has been found preferable to use for this purpose the arrangement of Fig. 10, which is shown especially in its application to the embodiments of Figs. 1 and 2, although a similar arrangement can obviously be used also for that of Figs. 3 and 4, as will be apparent from the following.

A collar or sleeve member 125 is slidably fitted over the drill stem above the sliding cylinder 5A. A spring 128 has its upper end connected to a pin 121 affixed to the drill string, and its lower end connected to said sleeve member as shown at 122, being thus held in tension and tending to pull the sleeve upwards. The sleeve 125 has formed therein inclined or slanting slots 139, adapted to receive pins or fingers 137, affixed to the drill stem. The lower rim of the sleeve member 125 has formed thereon an annular row of teeth 131, adapted for a gripping engagement with teeth 134 formed on the upper end of the reciprocating cylinder member 5A. A plurality of spring members 133 maintain a frictional engagement between the sleeve and the cylinder members, being attached to one, for example to the sleeve 125, as shown in Fig. 10, and dragging over the surface of the other, for example the cylinder 5A, on which a band of serrations 135 may be provided to improve the frictional grip.

In operation, when the bit is on the bottom and it is desired to switch from percussion to rotary drilling, the drill string is lowered as far down as possible, and is rotated in the proper direction, for example clockwise with the arrangement shown in Fig. 10. The pins or fingers 137 rotate with the string, while the sleeve 125, due to the frictional effect of the springs 133, lags behind, thus causing the fingers 137 to travel to the other end of the slots 139, lowering the sleeve 125 and permitting the teeth 131 to engage the teeth 134, whereafter the bit may be rotated from the surface by means of the drill string. When it is desired to stop rotary drilling, the drill string is raised, disengaging the teeth, and the tension spring 128 pulls the sleeve 125 further up to protect the teeth from blows when the percussion or impact drilling is resumed.

If it is desired to make, by impact drilling, a hole having a diameter larger than that obtainable with a bit of a particular size used, this may be effected, for example, by welding two of the cutting elements 142, on opposite sides of the bit at a slight angle with regard to the axis of the bit, as shown in Fig. 7A. This causes the bit to be deflected towards the side of the element 140 on the downward stroke, and in the opposite direction on the upward stroke, said second deflection being however smaller because of the smaller speed during the upward stroke.

A similar result may also be achieved by locating the center of gravity of the bit away from the axis of the bit, that is, away from the line of action of the driving force. As shown in Fig. 8, this may be effected by means of an asymmetrical arrangement of the cutting blades, for example by omitting one of the blades of a regular four-blade bit, and by reinforcing the blade 113 which is positioned on that side towards which the bit is deflected and which does therefore most of the cutting work.

Since the present system is adapted for uninterrupted operation throughout extended periods of time, it is sometimes advisable to provide it

with an arrangement adapted to indicate to the driller that the drill is worn beyond a safe point and to stop the reciprocating action automatically before damage is done to the present valve system located above the bit. Figs. 11 and 12 show such an arrangement, wherein a bit 151, which may be of any of the types described hereinabove, is provided with an axial passage 153 and a plurality of radial or lateral passages 152 in communication therewith for exhausting or circulating the hydraulic or drilling fluid. The bit has formed therein in register with said passage 153 a well or cavity 156, in which a steel plug 155 is held, for example by brazing, spot welding or soft soldering. The plug 157 has a downwardly tapering conical shape and a diameter selected so that when, as shown in Fig. 12, the bit is worn beyond a safe point, the direct hammering or pounding effect of the plug 157 against the bottom of the borehole results in detaching said plug from the copper, lead or other matrix retaining said plug in the well 156, and in forcing it against the passage 153, which closes said passage and automatically stops the reciprocating action of the bit by interrupting the flow of the hydraulic fluid.

Since the liquid throughput of the present bit is subject to considerable variations during each cycle, water hammer effects may sometimes occur in operation. To eliminate these effects, and at the same time to provide the proper volume of circulating liquid for flushing the borehole, a special valve may be provided whereby the fluid consumption of the bit is regulated or held at a desired value. This valve may be mounted either in the working cylinder of the present device, or in the drill string at any suitable distance above the bit. Fig. 13 shows an enlarged section 163 of the drill string 161, which is provided with a port or ports 169. A beam spring 167 is securely clamped to the wall of the pipe section 163, and tends to maintain the port 169 normally closed. When the pressure differential between the inside and the outside of the pipe exceeds a maximum predetermined by the setting or strength of the spring 167, the valve 171 opens, and permits a portion of the liquid to by-pass the drill bit.

The working cylinder of the bit, or of the drill pipe, may also be provided with additional ports 175, and the system may be operated with these ports either open, or closed by means of removable plugs 173, depending on the volume of the fluid which it is desired to circulate in the bore-hole.

During the drilling process, it may sometimes be desired to move the bit up or down within the borehole, for example for the length of the kelly, without shutting off the circulation.

In order to enable the operators to do so without permitting the reciprocating action of the present system to start or to continue (which is dangerous when the bit is away from the bottom, since the force of the blows is in such cases brought to bear on the shoulder contact between the piston and the cylinder, with ensuing damage to the equipment), the arrangement shown in Fig. 14 may be used for the bits of the type shown in Figs. 1 and 2.

The inside walls of the upper portion of the reciprocating cylinder 5B are provided with relatively shallow grooves 181, having a longitudinal or axial length greater than that of the piston 15B. When the drill stem 1B is lifted until the piston 15B is stopped by contact with the upper

closure shoulder of the cylinder, the grooves 181 provide a by-pass for the hydraulic fluid around said piston, whereby no pressure rise is permitted to develop in the space above the piston 15B, as described with regard to Figs. 1 and 2, and the reciprocating action is not permitted to take place.

The same result is obtained with regard to the bits of the type shown in Figs. 3 and 4 simply by giving the ports 83 a vertical or axial length greater than that of the piston 65, whereby fluid is admitted to the space above the piston when the piston is in its lowermost position.

I claim as my invention:

18. A hydraulic device adapted to be lowered on a drill string into a borehole for impacting a drill bit against the bottom thereof, said device comprising cylinder and piston members, one of said members being attached to said drill string and the other member being attached to said drill bit and movable with regard to said string, and variable stroke means for reciprocating the movable member, said means comprising passage means for admitting a pressure fluid from the drill string to the cylinder member to one side of said piston, passage means for exhausting the fluid from the cylinder on the other side of the piston, a passage through the piston, said passage having a restricted portion, a hollow cup-shaped valve adapted to close said piston passage to fluid flow during the upward stroke of the movable member, a cap member affixed to the piston member in register with the open face of the cup-shaped valve, pin means affixed to the cylinder member adjacent the passage means for exhausting the fluid therefrom adapted to force said valve to an open position in contact with said cap member at the end of said upward stroke, and channel means through the walls of the cup-shaped valve in communication between the restricted portion of the piston passage and the closed space defined within the cup-shaped valve when said valve is in contact with said cap member, whereby said cup-shaped valve is maintained in an open position in contact with said cap member by a Venturi suction effect created by the fluid flow through said restricted portion of the piston passage during the downward stroke of the movable member, and is released to a closed position by a decrease of said fluid flow and of said suction effect occurring when the motion of the movable member is arrested by the impact of the drill bit against the bottom of the borehole.
20. A hydraulic device adapted to be lowered on a drill string into a borehole for impacting a drill bit against the bottom thereof, said device comprising cylinder and piston members, one of said members being attached to said drill string and the other member being attached to said drill bit and movable with regard to said string, and variable stroke means for reciprocating the movable member, said means comprising passage means for admitting a pressure fluid from the drill string to the cylinder member to one side of said piston, passage means for exhausting the fluid from the cylinder on the other side of the piston, a passage through the piston, said passage having a restricted portion, a hollow cup-shaped valve adapted to close said piston passage to fluid flow during the upward stroke of the movable member, a cup member affixed to the piston member in register with the open face of the cup-shaped valve, pin means affixed to the cylinder member adjacent the passage means for ex-

hausting the fluid therefrom and adapted to force said valve to an open position in contact with said cap member, channel means through the walls of the cup-shaped valve in communication between the restricted portion of the piston passage and the closed space defined within the cup-shaped valve when said valve is in contact with said cap member, whereby said cup-shaped valve is maintained in an open position in contact with said cap member by a Venturi suction effect created by the fluid flow through said restricted portion of the piston passage during the downward stroke of the movable member, and is released to a closed position by a decrease of said fluid flow and of said suction effect occurring when the motion of the movable member is arrested by the impact of the drill bit against the bottom of the borehole, a valve affixed to the movable member and adapted to seat against the fluid exhaust passage, spring means tending to maintain said valve open, yieldable means adapted to force said valve closed by contact therewith at the end of the upward stroke of the movable member, said valve being adapted to remain closed by fluid pressure within the cylinder against the action of said spring means during the downward motion of said movable member, and leakage means through the walls of the movable member adapted to relieve said pressure, whereby said valve is maintained open by said spring means during the upward stroke of said movable member.

3. A hydraulic device adapted to be lowered on a drill string into a borehole for impacting a drill bit against the bottom thereof, said device comprising a piston attached to said string and a cylinder adapted for reciprocation about said piston, said cylinder having the bit attached thereto, passage means for admitting a pressure fluid from said string to said cylinder above said piston, passage means for exhausting the fluid from the cylinder below said piston, a passage through the piston, said passage having a restricted portion, a hollow cup-shaped valve adapted to close said piston passage to fluid flow during the upward stroke of the cylinder, a cap member connected to the piston member above the cup-shaped valve in register with the open face thereof, yieldable pin means affixed to the cylinder below said piston adapted to force said valve to an open position with its open face in contact with said cap member at the end of said upward stroke, and channel means in fluid communication between the restricted portion of the piston passage and the closed space defined within the cup-shaped valve when said valve is in contact with said cap member, whereby said cup-shaped valve is maintained in an open position in contact with said cap member by a Venturi suction effect created by the fluid flow through said restricted portion of the piston passage during the downward stroke of the cylinder, and is released to a closed position by a decrease of said fluid flow and of said suction effect occurring when the motion of the cylinder is arrested by the impact of the drill bit against the bottom of the borehole.

4. The device of claim 3, comprising coil spring means disposed below the piston within the cylinder, said spring means being adapted to be compressed between the piston and the cylinder during the upward stroke of the cylinder and to expand during the downward stroke of the cylinder.

5. The device of claim 1, having a clutch for imparting a rotary motion to the drill bit by means of the drill string, said clutch comprising

12

a first annular toothed member fixedly connected to the drill bit member of the device, a second annular toothed sleeve member concentric with the drill string member of the device and adapted for sliding motion with regard thereto, pin and slot means connecting said sleeve and drill string members and adapted to translate a rotational motion of the drill string member into an axial motion of the sleeve member, whereby said toothed sleeve member is caused to engage the toothed member connected to the drill bit member, spring means frictionally connecting said sleeve and said drill bit members, and spring means engaged between said sleeve and said drill string members and adapted to urge said sleeve member away from said first toothed member.

6. The device of claim 1, having as fluid exhaust means an axial bore extending into the drill bit, radial passages in communication between said bore and the outside of the bit, an axial cavity in the body of the bit in register with said bore below said passages, a metallic plug in said cavity, and frangible means retaining said plug in said cavity, said plug being adapted to be pressed out of said cavity and into contact with said bore to close said bore by direct pounding against the bottom of the borehole when the lower part of said bit is worn out to the level of said plug.

30. 7. The device of claim 1, having radial port means in fluid communication between the inside and the outside of the drill string above said piston member, valve means adapted to close said ports, and spring means adapted to maintain said valves closed at fluid pressures within said drill string below a predetermined maximum.

8. A hydraulic device adapted to be lowered on a drill string into a borehole for impacting a drill bit against the bottom of the borehole, said device comprising a cylinder member and a piston member, one of said members being attached to the drill string and the other member being attached to the drill bit and being movable with regard to the drill string, and variable stroke means for reciprocating the movable member, said means comprising passage means for admitting a pressure fluid from the drill string into the cylinder member to one side of the piston member, passage means for exhausting said fluid from the other side of the piston member, a passage through the piston member, said passage having a restricted portion, a cap member rigidly connected to the piston member above said passage and coaxially therewith, a hollow cup-shaped valve member adapted to close said passage to fluid flow during the upward stroke of the movable member, pin means carried by the cylinder member below said piston adapted to force the open face of said hollow valve member against said cap member at the end of the upward stroke, thereby opening said passage to fluid flow, and channel means through the walls of the cup-shaped valve in communication between the restricted portion of the piston passage and the closed space defined within the cup-shaped valve when said valve is in contact with said cap member, whereby said cup-shaped valve is maintained in an open position in contact with said cap member by a Venturi suction effect created by the fluid flow through said restricted portion of the piston passage during the downward stroke of the movable member, and is released to a closed position by a decrease of said fluid flow and of said suction effect occurring when the motion of the movable member is arrested by the impact of the drill bit against the bottom of the borehole.

70. 60. 65. 75. The device of claim 1, having a clutch for imparting a rotary motion to the drill bit by means of the drill string, said clutch comprising

of the drill bit against the bottom of the bore-hole.

9. A hydraulic device adapted to be lowered on a tubular string into a borehole for impacting a drill bit against the bottom thereof, said device comprising a cylinder and a piston, said piston being attached to the string and said cylinder being attached to the bit and movable with regard to the string, and variable stroke means for reciprocating the cylinder, said means comprising passage means for admitting a pressure fluid from the string to the cylinder above the piston, passage means for exhausting the fluid from the cylinder below the piston, an axial passage through the piston, said passage having a restricted portion, a cap member affixed to the piston co-axially with said passage, a movable hollow cup-shaped valve member adapted to close said piston passage to fluid flow during the upward stroke of the cylinder, said cup-shaped valve member having an open face in register with said cap member, pin means affixed to the cylinder below said piston adapted to force the open face of the cup-shaped valve member into a position in contact with said cap member at the end of the upward stroke of the cylinder, thereby opening the piston passage, and channel means in
